UNITED STATES PATENT OFFICE.

NORMAN W. NUTT, OF TRENTON, NEW JERSEY.

COMBINED ELECTRIC LAMP SOCKET AND SHADE HOLDER.

Application filed July 27, 1920. Serial No. 399,438.

To all whom it may concern:

Be it known that I, NORMAN W. NUTT, a citizen of the United States, residing at Trenton, in the county of Mercer, State of New Jersey, have invented a Combined Electric Lamp Socket and Shade Holder, of which the following is a specification.

This invention relates to a combined electric lamp socket, including the customary switch mechanism, and a shade holder, the two parts being so associated and assembled that the usual shell or casing for the lamp sockets may be dispensed with, the said shade holder performing the function of a socket shell or casing, in addition to a support for the lamp shade.

The salient object of this invention is to provide a fixture of this type simple in design and construction and one that is very desirable from a practical standpoint, for the reason that the same can be cheaply produced.

Another object of the invention is to provide a simple and efficient means for supporting or securing the switch mechanism to the nipple or the like usually employed for attaching the fixture to its supporting bracket or pipe section conveying the wires to the terminal point.

A still further advantage of this construction will be apparent, in that the means for securing the switch mechanism to the nipple also provides a simple yet substantial support for the shade holder.

The invention also contemplates the provision of a spacing member positioned between the lower end of the lamp socket and the lower end of the shade holder for positively positioning and always maintaining the socket and switch mechanism in its proper position within the shade holder, said spacing member being so constructed that the same may be readily detachable.

Another feature of the invention is the particular means of supporting the spacing member within the lower portion of the shade holder adjacent the thumb screws employed for securing the shade within the holder, in such a manner that said screws may be entirely removed when desired to remove the shade, without disturbing or displacing the spacing member.

Briefly stated, the invention comprises the usual two part porcelain switch mechanism, including the screw threaded terminal for the electric lamp, and a yoke comprising an

annular collar and downwardly and inwardly bent leg portions, the collar adapted to be swaged to the securing nipple or the like and the leg portions attached to the upper face of the porcelain switch mechanism, which yoke construction forms a strong and rigid support for said switch mechanism.

Completely enveloping the yoke and switch mechanism and forming substantially a casing therefor is a shade holder having an enlarged lower end and provided with means for supporting in said lower end a lamp shade of the usual construction. The upper or cap portion of the shade holder is sup-

ported upon and snugly embraces the yoke supporting the switch mechanism, said yoke forming the double function of a support for the switch mechanism and the shade holder. Interposed between the shade holder and said switch mechanism is an insulating fiber shell or casing projecting downwardly

and also enclosing the screw terminal of the electric lamp attached to the porcelain supporting the switch mechanism. Positioned

between the lower end of this insulating shell and the lower end of the shade holder is a centering or spacing member forming a simple yet efficient means for positively positioning the insulating shell surrounding

the switch mechanism, within the shade holder, the details of which will be herein-after more fully set forth.

The invention embodying the several features above related is illustrated in the accompanying drawings, in which:

Fig. 1 is a view partly in section and partly in elevation, illustrating the preferred form of the invention with the shade holder made in two separable parts;

Fig. 2 is a bottom plan view thereof with the lamp socket removed;

Fig. 3 is a view on line 3-3 of Fig. 2, illustrating the means of supporting the spacing member within the shade holder;

Fig. 4 is a detail view in elevation illustrating the means of securing the yoke to the upper face of the porcelain supporting the switch mechanism;

Fig. 5 is a plan view thereof;

Fig. 6 is a sectional view on the line 6-6 of Fig. 5; and

Fig. 7 is a view partly in elevation and partly in section of the assembled device, employing a one-piece shade holder and a slightly modified means of spacing member.

Referring to the drawings in detail, the

lamp socket supporting base made of molded porcelain or similar insulating material, comprises the usual upper and lower sections 1 and 2, supporting therebetween the 5 switch mechanism 3 operated by the conventional key 4. The lower section 2 has supported therefrom the electric lamp screw terminal 5 which is of the usual construction. Secured to the upper face of the porcelain 10 1, by screws or the like 7, is a supporting yoke provided with an annular collar 8 and a pair of downwardly and inwardly projecting curved legs 9. Collar 8 is positioned about and adapted to be 15 swaged or similarly secured to a nipple 10, which nipple is of the usual type employed for supporting the entire fixture from a bracket or the like. With this construction the entire lamp socket is securely and definitely supported from the nipple.

Completely enveloping the entire switch mechanism and socket is a shade holder 11 which not only forms a support for the shade holder but acts as a shell or casing for the 20 porcelain socket and thereby doing away with the usual metallic shell or casing generally employed with these sockets. The lower end of the shade holder 11 is flared outwardly and provided with an inwardly 25 curved portion 12 which is adapted to receive and have secured therein the desired form of lamp shade, by thumb screws or the like 13, which thumb screws are threaded into bushings 14 secured in the curved portion 30 12 of the shade supporting end of the shade holder. Interposed between the shade holder and socket is an insulating fiber shell 15 which extends down below the screw terminal 5 of the lamp socket, the lower end 35 16 being of less diameter than the upper portion thereof and thereby providing a shoulder 17, to be hereinafter referred to. Positioned between the lower end 16 of the insulating shell 15 is a removable spacing 40 45 member or spider 18. This spacing member is formed with an upstanding annular collar 19 which is adapted to closely embrace the end 16 of the fiber shell, the upper edge of the collar abutting against the shoulder 17 50 which will prevent the displacement of the insulating shell. The spacing member or spider 18 is also provided with outwardly and downwardly extending legs 20, the outer ends of which closely embrace the inner face 55 of the lower edge of the shade holder and rest on the bushings 14, which bushings provide a support for the removable spacing member or spider. In order to insure a secure positioning of the spacing member 18, 60 after once being adjusted, and to prevent the legs 20 from becoming disengaged from the bushings 14, a portion of the bottom edge of said legs are provided with recesses or curved cut out portions 21, so that when the 65 leg portions of the spacing member are

snapped over the bushings, said spacing member will be secured thereon against any accidental or unintentional displacement. When it is desired to remove this spacing member it is only necessary to force the same 70 slightly to the right or left, whereupon the legs of the spider will become disengaged from the bushing and the same may be readily removed from this assembled position. The bushings 14 not only provide a substantial bearing for the screws 13, but by acting as supports for the removable spacing member or spider, the screws 13 may be freely manipulated, and in fact entirely withdrawn if necessary in removing the shade, without disturbing the spacing member or spider.

In one form of my invention, as illustrated in Fig. 1, the shade holder 11 is made in two separable sections and provided with a removable cap 11¹, the remaining portion of the shade holder being secured thereto by snap catches or the like.

In the construction, as illustrated in Fig. 7, the shade holder is made in one piece and also provided with a modified form of spacing member between the lower end of the insulating shell and the shade holder. In this construction the shade holder is provided with a screw threaded portion 22, 95 which is adapted to engage complementary threaded portions 23, of an annular spacing member 24. This spacing member 24 is constructed with a converged lower end 25 which closely embraces the lower end of the 100 insulating shell 15. It will be noted that this spacing member is likewise removable, as is the spacing member illustrated in Fig. 1.

As distinguished also from the construction of the shade holder illustrated in Fig. 1, clamping screws 13 may be positioned in downwardly extending projections 13¹ formed on the lower end of the shade holder, as shown in Fig. 7. In this construction the 110 lower end 12 of the shade holder will not have to be made as large, relatively as the portion 12, as illustrated in Fig. 1, wherein the clamping screws for the shade are positioned in the main part of this lower portion 12.

From the foregoing description it will be apparent that applicant has devised a very simple, strong, and practical combined lamp socket and shade holder, possessing a minimum number of parts, easily assembled and adjusted and a fixture that is not only cheap to manufacture but combining therewith all the features and appearance of a finished product.

What I claim is:

1. The combination with a shade holder, of an electric lamp switch mechanism including a screw terminal forming a lamp socket, a yoke for supporting said socket from a se- 130

curing nipple, said shade holder being supported upon said yoke and forming a casing for the socket, an insulating shell interposed between the socket and shade holder and a removable spacing member comprising an annular collar adapted to embrace the lower end of the insulating shell, having outwardly and downwardly extending legs engaging the inner lower end of said shade holder for centering said shell within the shade holder.

2. The combination with a shade holder, of an electric lamp switch mechanism including a screw terminal forming a lamp socket, a yoke for supporting said socket from a securing nipple, the lower ends or legs of said yoke adapted to be secured to the upper face of the socket, said shade holder being supported upon and closely embracing outwardly and downwardly extending portions of said yoke and forming a casing for the socket, the lower end of said shade holder provided with an inwardly curved annular flange, screw threaded bushings carried by said flange, thumb screws for clamping a shade within said annular flange threaded into said bushings, an insulating shell interposed between the socket and shade holder and a removable spacing member comprising an annular collar adapted to embrace the lower end of the insulating shell having outwardly and downwardly extending legs engaging the inner face of the curved annular flange, said legs being provided with recesses for engaging with the screw bushings, for supporting said spacing member in its assembled position.

NORMAN W. NUTT.
